DESIGN FOR AN AIRCRAFT PROPELLER

Max M. Munk, Cottage City, Md.

Application January 12, 1942, Serial No. 105,146

Term of patent 14 years

To all whom it may concern:

Be it known that I, Max M. Munk, a citizen of the United States, residing at Cottage City, in the county of Prince Georges and State of Maryland, have invented a certain new, original, and ornamental Design for an Aircraft Propeller, of which the following is a specification, reference being had to the accompanying drawing, forming a part thereof.

The present application is a continuation-in-

part of application Serial Number D-102,916, filed Aug. 18, 1941.

Fig. 1 is an oblique elevational view of an aircraft propeller embodying my design.

Fig. 2 is a front elevational view thereof, and Fig. 3 is a side elevational view thereof.

I claim:

The ornamental design for an aircraft propeller, substantially as shown and described.

MAX M. MUNK.
